UNITED STATES PATENT OFFICE.

CHAMPLAIN L. BILEY, OF NORTH PLAINFIELD, NEW JERSEY, ASSIGNOR TO INDUSTRIAL ASSOCIATES, INCORPORATED, OF NEW YORK, N. Y., A CORPORATION OF NEW YORK

NEBULIZER.

Application filed November 21, 1925. Serial No. 70,532.

My invention relates to nebulizers, and particularly to nebulizers of centrifugal type. My invention provides certain improvements over the construction shown in my Patent 1,624,847, particularly with reference to (1) the centrifugal dispersion of the liquid, (2) the shaping of the rotor to minimize adhesion of solids, and (3) the mounting of the rotor on its driving spindle.

10 In the accompanying drawings—

Fig. 1 is a side elevation partially in section illustrating a nebulizer which incorporates my improvements; and

Fig. 2 is a plan view of the rotor alone.

15 The present nebulizer comprises a rotor having a spherical hub 15 axially pierced at 16 to freely accommodate the bolt 17 by which it is attached to the driving spindle 18. A hemispherical seat 19 is provided at 20 the end of the spindle to engage the upper face of the hub 15, and a corresponding hemispherical seat is provided in the face of the washer 20 which underlies the rotor and is supported by the nuts 21 at the lower 25 end of the bolt 17. The spindle is driven at high speed (say 5000 revolutions per minute) by any suitable means, such as a belt engaging the pulley 22 on the spindle.

Extending from the hub 15 in its plane 30 of rotation is a web 23, preferably integral therewith. Rigid with the web and also preferably integral therewith, is a speed ring 24. In the form shown the speed ring is duplex and extends on both sides of the 35 plane of the web. On its inner face, the speed ring is concaved to form a pair of like channels 25, 26 at opposite sides of the web, but communicating with each other through apertures 27 located in the peripheral area 40 of the web adjacent the speed ring.

The margins 28 and 29 of the channels are 45 equally spaced from the axis of rotation, and also from the web 23. These margins are preferably rounded and merge smoothly into the upper and lower annular dispersing surfaces 30 and 31 of the speed ring. These end surfaces are dished or bevelled and converge toward the axis of the rotor forming throw-off lips, the outer margins 32, 33, of 50 which constitute sharp throw-off edges. Connecting the latter is the peripheral surface 34 of the ring which is dished or concaved for a purpose hereinafter explained.

The liquid to be dispersed is led to the

rotor through pipe 35 and discharges from nozzle 36 to the upper surface of the web 23. It is at once thrown outward by centrifugal force to the bottom of the channel 35, where it is held by the same force and rapidly acquires the rotary speed of the ring 34. As the stream of liquid continues to flow through the nozzle 36, its radial depth in the channel 25 increases until the outer peripheries of the holes 27 are reached, whereupon the liquid, under the action of centrifugal force, passes through the holes 27 and enters the channel 26 until equal radial depth of liquid is attained therein. The radial depth of the liquid in the two channels now increases steadily and equally as liquid continues to feed through the nozzle 36, the walls of the channels serving as dams which prevent the outward escape of the liquid. The latter thus forms in effect two liquid annuli, one on each side of the web 23, both annuli 70 rotating at high speed under the drag of the speed ring and web.

The rapidly rotating liquid annuli finally attain a radial depth sufficient to over-flow the smooth crests 28 and 29 of the confining dams. The over-flow is at once dispersed outwardly by centrifugal force, and the liquid leaves the throw-off edges of the speed rings at the speed of rotation acquired while detained in the whirling liquid annuli, combined with the radial speed imparted thereto by the centrifugal throw-off. Moreover, the depth of each sheet of liquid over-flowing the dam crests 28 and 29 is reduced as it fans out over the radially increasing area 90 of the surfaces 30, 31. Consequently, the liquid reaches the throw-off edges 32, 33 in attenuated form, and is discharged therefrom at exceedingly high speed against the surrounding atmosphere. Not only the impact against the air wall, but the forces of disassociation incident to the high discharge speed, cause the liquid to break into a very fine nebula. This condition is ideal for spray drying, gas washing, air conditioning, etc.

In spray drying, the solids, freed from their moisture and in very fine condition, tend to gather upon bodies with which they come in contact. In the nebulizer shown in my application above mentioned, the throw-off lips are located radially inward from the periphery of the rotor, with the result that

when used for spray drying the solids tend to gather on these peripheral surfaces. They not only add weight to the rotor, but they are apt to set up an unbalanced condition which is hard on the bearings, and may even result in a wabbling action which endangers the rotor itself. In the present construction, the peripheral surface of the rotor or speed ring is concaved or dished and lies radially inward from the outer margins of the dispersing surfaces. The dispersed liquid is thrown outward entirely clear of the peripheral surfaces of the rotor, and the latter do not gather solids to any substantial extent. Moreover, the radial extent of the dispersing surfaces is greater than in my earlier construction, and a greater centrifugal off-throw speed is imparted to the particles of the dispersed liquid film. Again, the inclination of the centrifugal dispersing surfaces is such that the fluid is directed outwardly in planes which diverge from the plane of the rotor. This also tends to keep the solids away from the rotor and prevents deposition thereon.

The present construction thus adds to the advantage of a liquid ring rotating at high speed, and a centrifugal discharge from its margins, as in my prior application, the advantage of (1) a centrifugal off-throw surface of greater radial extent, (with resultant higher off-throw speed and greater attenuation of the liquid before discharge) (2) a discharge directed away from the plane of rotation, and (3) a discharge at a point beyond the peripheral surface of the rotor.

From a structural standpoint the present rotor is quite as simple to manufacture as my earlier form, and it has the advantage of a self-centering bearing connecting to a driving spindle. The nuts 21 are tightened to such point that the rotor can be moved only with difficulty, by hand. When rotating at high speed however, centrifugal force causes the rotor to find its exact plane of rotation, while the friction exerted upon the hub 15 suffices to effect the drive.

While I have shown the construction which I regard as the best now known to me, various modifications will readily occur to those dealing with the problem, which fall within the scope of what I claim as my invention.

I claim—

1. In a centrifugal atomizer, a driving spindle and a nebulizer unit suspended therefrom and having a frictional flexible joint drive engagement therewith.

2. In a centrifugal atomizer, a driving spindle having concave seat at one end, a nebulizer unit having a ball hub fitted to said seat and axially pierced, a cup member bearing against the opposite face of said ball hub, and a clamping member passing through the axially pierced hub and engaging the spindle to secure the said parts together.

3. In a centrifugal atomizer, a driving spindle having concave seat at one end, a nebulizer unit having a ball hub fitted to said seat and axially pierced, a cup member bearing against the opposite face of said ball hub, and a clamping member passing with clearance through the axially pierced hub and engaging the spindle to secure the said parts together.

4. In a centrifugal atomizer, a rotor comprising an annulus concave on its inner periphery to form a channel and concave on its outer periphery, the surfaces connecting the margins of said inner and outer periphery concave surfaces constituting throw-off lips, the peripheral margins of which project beyond the outer peripheral surface of the annulus.

5. In a centrifugal atomizer, a rotor comprising an annulus having end surfaces forming throw-off lips and an outer peripheral surface connecting said end surfaces, said outer peripheral surface being concave.

6. In a centrifugal atomizer, a rotor comprising an annulus having inner and outer peripheral surfaces and end surfaces connecting said peripheral surfaces, said end surfaces forming throw-off lips, and said outer peripheral surface being concave.

7. In a centrifugal atomizer, a rotor comprising an annulus having inner and outer peripheral surfaces and end surfaces connecting said peripheral surfaces, said end surfaces being convergent toward the axis and said outer peripheral surface being concave.

In testimony whereof I have signed my name to this specification.

CHAMPLAIN L. RILEY.
